INVENTOR
M. WEINBERGER

BY J. M. Wright,
ATTY.

UNITED STATES PATENT OFFICE.

MARCUS WEINBERGER, OF SAN FRANCISCO, CALIFORNIA, ASSIGNOR OF ONE-THIRD TO
OTTO BONAKER, OF SAN FRANCISCO, CALIFORNIA.

BATH-TUB ATTACHMENT.

1,297,980.

Specification of Letters Patent. Patented Mar. 18, 1919.

Application filed November 12, 1918. Serial No. 262,142.

To all whom it may concern:

Be it known that I, MARCUS WEINBERGER, a citizen of the United States, residing at San Francisco, in the county of San Francisco and State of California, have invented new and useful Improvements in Bath-Tub Attachments, of which the following is a specification.

It is a matter of common experience in taking a bath in an ordinary bath tub, especially with elderly persons, or those partially lame, weak, or otherwise disabled, that it is not an easy matter to rise and step from the bath tub with safety. Serious accidents, and even death, have been caused by slipping when rising stepping out of a bath tub.

One object of my invention is to provide means which can be attached to any ordinary bath tub, and which can be used to assist the bather in leaving it.

A further object is to provide, in combination with such means, convenient means, adjustable for use by persons of all sizes and forms, whereby the bather can readily brush or scrub any part of his back while sitting in the bath tub.

In the accompanying drawing, Figure 1 is a perspective view showing my improved attachment in use as a scrubbing or cleansing means; Fig. 2 is a broken plan view of the attachment on an enlarged scale; Fig. 3 is a cross-sectional view on the line 3—3 of Fig. 2; Fig. 4 is an enlarged vertical section on the line 4—4 of Fig. 1, showing also a portion of a bath tub; Fig. 5 is a horizontal section on the line 5—5 of Fig. 4; Fig. 6 is a partial longitudinal vertical sectional view of a modified form of the invention.

Referring to the drawing, 1 indicates a bath tub, which, in the form of the invention shown in Figs. 1 to 5, is of metal, enameled, or otherwise. Through the periphery of said bath tub, at its foot, is formed a hole 2, (Fig. 4) which is elongated in a direction transverse to the bath tub. Through this hole is inserted a pin 3, extending axially from the bottom of a bearing 4, which pin 3, in the form of the invention shown in Figs. 4 and 5, has upper and lower portions out of alinement and an intervening elbow or bend 6, the pin, in order to insert it in said hole 2, being placed in the position in which the bend extends in a

direction transverse to the bath tub, and then, when the upper portion of the pin is in the hole, being turned so that the bend extends in the longitudinal direction of the bath tub, thus retaining the pin in place. 60

In the form of the invention shown in Fig. 6, in which a porcelain bath tub is shown, there is shown a much deeper hole, and a straight pin 3^a is used, since the bend in the pin is not then necessary to hold it in 65 place when the attachment is in use.

The upper portion of said bearing 4 is forked, as shown at 7, and in said fork is inserted a reduced flattened end of a pivot piece 8, swinging upon a shaft 9 formed by a screw extending transversely through said fork 7, and on the projecting threaded end of said shaft 9 is screwed a wing-nut 11, so that by screwing said wing-nut tight against said fork 7 the pivot piece can be clamped 70 to extend in any desired direction about the shaft. In the enlarged other end of said joint is a threaded socket 12, into which is screwed a threaded reduced rounded end of a long rod 13, preferably rectangular in 75 cross-section. On said rod and extending on both sides thereof is a handle 14 adjustably secured on said rod by a thumb screw 16 screwed through a portion of said handle and into one of a longitudinal series of suitably spaced recesses 17 formed in one side of the rod. By means of said screw 16, the handle 14 is thus firmly secured upon the rod, and, in the handle, therefore, the bather finds a very firm and yet adjustable support 80 against slipping and falling when rising from the bath tub. 85

However, I also use this rod as part of a cleansing device, and, with this in view, upon its free end is secured, by a thumb screw 18, 95 an arm 19, rectangular in cross section, and a side of which forms a dove-tailed rib 21. 22 indicates a brush back, having in its rear surface a dove-tailed groove 23 which is engaged by the dove-tailed rib 21. The brush 100 back can be secured in any desired position by means of a screw 25 screwed into said arm and bearing against said back. To the front side of said back is removably secured, by screws 26, a brush 27 of any desired character. 105

The mode of operation of this part of the attachment will be readily understood by the foregoing description.

The bather can move the brush over his 11

back either up or down or from side to side, and can adjust the position of the brush to vary its distance either from the pivot piece 8 or from the rod 13.

- 5 The attachment when not in use can either be supported against a wall or other support, or can lie in the bath tube.

I claim:

A bathtub attachment comprising a support provided with means for removably

securing it to a bathtub, a rod pivotally connected to said support about a horizontal axis transverse to the tub, a handle adapted to be grasped by a bather, means for securing said handle at any one of spaced points on said rod, an arm, a brush longitudinally adjustable upon said arm, and means for securing an end of said arm at any one of spaced points on the rod. 15

MARCUS WEINBERGER.
